(57) **CLAIM**

The ornamental design for a CD printer, as shown and described.

DESCRIPTION

FIG. 1 is a top plan view of a CD printer showing our new ornamental design;

FIG. 2 is a front view thereof;

FIG. 3 is a side view thereof, the opposite side view being a mirror image thereof;

FIG. 4 a rear view thereof;

FIG. 5 is a left side perspective view thereof; and,

FIG. 6 is a right side perspective view thereof.

The dashed lines are for illustrative purposes only and form no part of the claimed design.
